IMPLEMENT HANDLE

John W. Davies III, Plymouth, Wis., assignor to Gilson Bros. Co., Plymouth, Wis., a corporation of Wisconsin

Filed Oct. 28, 1964, Ser. No. 82,358

Term of patent 14 years

(Cl. D35—2)

FIGURE 1 is a perspective view of an implement handle embodying the present invention as attached to a tiller.

FIGURE 2 is a front elevation of the implement handle.

FIGURE 3 is a side elevation of the implement handle.

FIGURE 4 is a cross section taken along the line 4—4 of FIGURE 2.

FIGURE 5 is a cross section taken along the line 5—5 of FIGURE 2.

FIGURE 6 is a fragmentary cross section taken along the line 6—6 of FIGURE 2.

FIGURE 7 is a fragmentary cross section taken along the line 7—7 of FIGURE 2.

The dotted line showing is for illustrative purposes only.

The characteristic feature of the design is the configuration of the opening at the lower end of the broad face panel, in the shape of a truncated pyramid having straight upwardly tapering sides and a straight top.

I claim:

The ornamental design for an implement handle, as shown and described.
